UNITED STATES PATENT OFFICE

GORDON MILLER BUEHRIG, OF INDIANAPOLIS, INDIANA, ASSIGNOR TO MANNING & CO., OF CHICAGO, ILLINOIS, A CORPORATION OF ILLINOIS

DESIGN FOR A COMBINED AUTOMOBILE RADIATOR AND FRONT

Application filed December 21, 1931. Serial No. 42,178. Term of patent 3½ years.

To all whom it may concern:

Be it known that I, GORDON MILLER BUEHRIG, a citizen of the United States, and a resident of Indianapolis, county of Marion, and State of Indiana, have invented a new, original, and ornamental Design for a Combined Automobile Radiator and Front, of which the following is a specification, reference being had to the accompanying drawing, forming a part thereof.

In the drawing Fig. 1 is a front view, Fig. 2, a fragmentary view in side elevation, and Fig. 3 a top plan view of a combined automobile radiator and front showing my new design.

I claim:—

The ornamental design for a combined automobile radiator and front substantially as shown.

GORDON MILLER BUEHRIG.
